(57) **CLAIM**

The design for an adjustable shelving system, as shown and described herein.

DESCRIPTION

FIG. 1 is a top side perspective view of my adjustable shelving system with shelving dividers shown in phantom; FIG. 2 is a front side plan view thereof; FIG. 3 is a back side plan view thereof;

FIG. 4 is a side plan view thereof with the opposite side being a mirror image of the side shown in FIG. 2; FIG. 5 is a top plan view thereof; and

FIG. 6 is a bottom plan view thereof; and,

FIG. 7 is a top perspective view of an alternative embodiment of my adjustable shelving system. Where used, the broken line portions of the disclosure are for illustrative purposes only and form no part of the claimed design.
